UNITED STATES PATENT OFFICE.

HOWARD M. DUDLEY, OF PHILADELPHIA, PENNSYLVANIA.

DYEING-MACHINE.

1,261,499.

Specification of Letters Patent.

Patented Apr. 2, 1918.

Application filed January 31, 1917. Serial No. 145,787.

To all whom it may concern:

Be it known that I, HOWARD M. DUDLEY, a citizen of the United States, and a resident of Philadelphia, in the county of Philadelphia and State of Pennsylvania, have invented certain new and useful Improvements in Dyeing-Machines, of which the following is a specification.

My invention relates to a dyeing machine and refers particularly to a machine adapted for the dyeing of textile fibers compressed within a dyeing chamber, the dyeing being accomplished by the forced passage of the dye liquor through the fiber mass.

Among the objects of my invention is a dyeing machine particularly suitable for the dyeing of warps in the ball, whereby the condition of the fiber may be accurately and readily judged at any stage of the treatment without opening the dyeing chamber and whereby even results may be obtained without disturbing the fiber to be dyed.

Another object of my invention is a dyeing machine in which the dyed goods may be after-treated with water, steam, air, or other materials or substances without handling the dyed goods.

Other objects of my invention will be evident upon a consideration of my specification and claims.

I have found that the even or uneven dyeing results obtained in a machine of this general character depend largely upon the particular shape of the openings through which the dye liquor enters the fiber mass, and that unevenness can be prevented by the use of openings of a particular shape, the conformation of which enables the liquor to spread itself through the fiber mass without the formation of channels of flow.

I have further found that this desirable result can be obtained if the fiber-mass is supported in the dyeing chamber upon a series of upwardly converging elements, as cones or pyramids, arranged with comparatively regularly disposed openings for the passage of the dye-liquor or other substances or material.

In the use of many dyestuffs it is necessary, after dyeing to treat the dyed goods with water for washing purposes, or with solutions of chemicals such as metallic salts or oxidizing products, for the purpose of after-treatment, or with oxygen or air for oxidizing or drying purposes. In the following of these after-treatments it is essen-

tial that every portion of the dyed goods be thoroughly and uniformly treated and that the operation be performed as readily and quickly as possible. All of these results are obtainable by the use of the device of my invention, in which the goods are placed in the dyeing chamber and then rapidly, easily and completely dyed and after-treated without further handling of the goods and without the formation of channels by the liquids employed. The device therefore insures even and uniform results with a minimum of time, labor and expense.

One form of my device is shown in the accompanying drawings in which similar parts are designated by similar numerals.

Figure 1 is a side view of one form of my invention, partly broken away to disclose a portion in cross-section.

Fig. 2 is a broken cross-section through the line 2—2 of Fig. 1.

Fig. 3 is a broken enlargement of a cross-section through the line 3—3 of Fig. 2.

Fig. 4 is a cross-section through the line 4—4 of Fig. 1.

Fig. 5 is a modified form of Fig. 4.

Fig. 6 is a cross-section through the line 6—6 of Fig. 5.

Fig. 7 is a broken top-plan view of a modification of the foraminous plate shown in Fig. 2.

Fig. 8 is a cross-section through the line 8—8 of Fig. 7.

Fig. 9 is a broken top-plan view of a modification of the foraminous plate shown in Fig. 2.

Fig. 10 is a cross-section through the line 10—10 of Fig. 9.

The outer portion of the dyeing machine, as illustrated, comprises the upwardly converging cover 12 removably attached to the annular member 13 by the screw bolts 14, 14, the member 13 being movably attached to the shell 15 by means of the screw bolts 16, 16, the shell 15 being attached to the shell 17 by the bolts 18, 18, the shell 17 being attached to the downwardly converging shell 19 by the bolts 20, 20, the shell 19 being attached to the centrifugal pump 21 by the bolts 22, 22. The pipe 23 connects the chamber of the pump 21 with the three-way pipe 24, the latter having the pipes 25, 26 and 27 fitted respectively with the valves 28, 29 and 30. The pipe 25 is connected with an air compressor not shown; the pipe 26 opens into the air and the pipe 27 may be connected with a drain.

or receptacle as desired. The pump 21 is connected with the pipe 31, which in turn is connected with the pipe 32, the latter being connected with the pipe 33 carrying the valve 34, the pipe 35 carrying the valve 36 and the pipe 37 carrying the valve 38. The pipe 33 is connected with a dye-dissolving tank, not shown, the pipe 35 is connected with a liquor-reserve tank 39, and the pipe 37 is connected with a water supply.

The object of the reserve tank 39 is to allow of the production and use of a larger quantity of dye liquor than is necessary to fill the dyeing device. By this means the strength 15 of the dye-liquor may be governed to meet the requirements of each individual dyeing operation, and the liquid maintained in a condition where the dye will not be precipitated upon the fiber. It also allows a more 20 uniform supply of liquor to the pump 21.

The annular member 13 is of angular shape, one arm of which 40 fits within the interior face of the shell 15 and is slidable therein, its vertical movement being governed by means of the screw-bolts 16, 16 which thread in the projections 41, 41 of the shell 15.

The pipe 42 connects the upper portion of the interior of the shell 15 with the liquor 30 reserve tank 39 and carries the valve 43. The pipe 44, carrying the valve 45 may be connected with a drain, not shown.

A fixed fiber-supporting plate 46 is situated between the shells 15 and 17 and comprises adjacently situated upwardly and downwardly converging pyramids 47, 47, having a series of openings 48, 48 for the passage of liquids, air, steam, etc.

The device is provided with a movable annular foraminous plate 50, the construction 40 of which is similar to the foraminous plate 46.

In order to facilitate reference to the various chambers, they will hereafter be referred to as the top chamber 51, the dyeing chamber 52, the liquor-supply chamber 53, and the lower chamber 54.

A sample dyeing machine 55 exactly similar to the one above described, except that it 50 is in smaller proportion and carries the threaded closed top 56 instead of the top 12, is connected to the liquor-supply chamber 53 by the pipe 57 carrying the valve 58. The upper portion of the sample machine 55 is 55 connected with a pipe 59, capable of being revolved into the position shown by the dotted line 60.

A pipe 61 connects the thermometer 62 with the liquor-supply chamber 54, the pipe 61 being extended beyond the thermometer into the pipe 63, capable of being revolved into the position shown by the dotted line 64.

A perforated steam pipe 65 is within the liquor supply chamber 53.

65 The top chamber 51 contains a series of

nested pyramidal shaped casings 66, 66 placed one within the other and supported by the diamond shaped bars 67, 67. A series of similarly nested pyramidal shaped casings 68, 68, supported by the members 69, 69 are 70 situated within the lower chamber 54.

The operation of the device is as follows:

The top 12, the annular member 13 and the foraminous plate 50 are removed, and the goods to be dyed introduced into the dyeing 75 chamber 52 upon the foraminous plate 46. The foraminous plate 50 is then placed upon the goods, and the annular member 13 introduced and moved downwardly by means of the screw bolts 16, 16 threaded in the projecting members 41, 41, the annular member 13 pressing upon the foraminous plate 50. This downward movement of the annular member 13 and the foraminous plate 50 is continued until the proper pressure has been 80 obtained upon the goods in the dyeing chamber 52. Goods are similarly placed in the sample device 55. Valves 45, 28, 29, 30, 38 and 34 are closed and valves 58, 43 and 36 are opened, and the pipes 59 and 63 situated 85 as shown by the dotted lines 60 and 64. The necessary dyestuff having been dissolved in the dye-dissolving tank, not shown, connected with the pipe 33, the valve 34 is opened and the centrifugal pump 21 is started. The 90 pump 21 forces the dye liquor upwardly between the nested pyramidal casings 68, 68 in the bottom chamber 54, the liquor supply chamber 53, the foraminous plate 46, the dyeing chamber 52 and the goods contained 95 therein. As the liquor rises it will pass through the overflow pipe 42 into the liquor-reserve tank 39, from which it will pass through the pipe 35 into the pump 21, thus allowing of a continuous circulation of the 100 dye-liquor upwardly through the device. During this operation the dye-liquor is forced upwardly through the sample device 55 and the goods contained therein. The 105 temperature is varied by means of steam introduced through the steam-pipe 65 and the temperature determined by means of the thermometer 62. From time to time, the valve 58 is closed, the top 56 of the sample device 55 removed and the goods contained 110 therein examined to determine their condition, and the top 56 replaced and the valve 58 opened and the dyeing operation continued until a test of the goods in the sample device shows them to be properly dyed.

The next step is the removal of the dye-liquor contained in the device. This is accomplished by closing valves 43, 34 and 36, opening valve 30 and stopping the pump 21. This allows all of the dye-liquor in the 115 device to drain through the pipe 27 into a suitable receptacle for future use if desired.

The next step is that of washing the excess of dye-liquor from the goods and this is accomplished by closing valve 30 and open- 120

130

ing valves 38, and 45, and starting pump 21. This allows fresh water to enter through the pipes 37, 32 and 31 into the pump 21 which forces it upwardly through the device and the goods contained therein and through the overflow pipe 44 into a drain.

The next step is that of oxidizing the dyeings, if oxidizable, by means of air or of drying the goods. This is accomplished by

10 placing the pipes 59 and 63 in the position shown by the full lines, placing the top 12 upon the device, affixing it thereto by means of the screw-bolts 14, 14, and attaching the upper open end of the top 12 to a vacuum 15 or suction pump, not shown. The valves 45 and 38 are closed, the valve 29 is opened, and the pump 21 stopped. The vacuum or suction pump attached to the top 12 thus draws air through the pipe 26 upwardly 20 through the device and the goods contained therein. If the amount of air thus obtained is insufficient for the purposes desired, the valve 28 connecting the pipe 25 with an air compressor may be opened and the valve 29 25 closed and thus sufficient air may be obtained. It is evident that the air passing through the pipes 25 and 26 may be heated before its introduction into the device, if desired.

30 The particular formation of the foraminous plate 46 causes the dye liquor to be spread out and evenly distributed through the goods, causing even dyeings, the plate 50, because of its similarity to the plate 46, 35 causes a more regular pressure of the dye liquor within the dyeing chamber 52 and the pyramidal members 66, 66 and 68, 68 intensify this distribution and regularity of pressure.

40 It is to be further noted that the goods are dyed, washed and after-treated or dried without handling, and that all of the operations are under exactly the same conditions, and that the condition of the goods 45 being dyed or treated can be determined at any time during the operation without interrupting the operation by examining the goods in the sample device 55.

In the modification shown in Figs. 5 and 50 6, the nested elements 70, 70 are conical in shape and are supported by the members 71, 71. In this modification it is advisable to have the top 12, the member 13 and the shells 15, 17 and 19, and the pump 21 of a 55 circular shape, the sample device 55 being also circular.

In the modification shown in Figs. 7 and 8, the foraminous plates 46 and 50 of Fig. 1 comprise a series of upwardly and downwardly converging pyramids 47, 47, the openings 72, 72 being situated at the adjacent corners of the pyramidal members.

In the modification shown in Figs. 9 and 10 the foraminous plates 46 and 50 of Fig. 1 65 comprise adjacently situated upwardly and

downwardly converging cones 73, 73, having a series of openings 74, 74 for the passage of liquids, air, steam, etc.

I do not limit myself to the particular size, shape, number or arrangement of parts 70 as illustrated and described, as any or all of them may be varied without going beyond the scope of my invention as described and claimed.

What is claimed, is:

1. In a dyeing machine, in combination, a receptacle, a lower foraminous plate comprising a series of upwardly and downwardly converging elements with openings between said elements, an upper foraminous 80 plate comprising a series of upwardly and downwardly converging elements with openings between said elements spaced from the lower plate, a fiber chamber formed by the two plates and the sides of the receptacle, means whereby air may be passed through the device, and means for forcing a liquid through the openings in the lower plate, the fiber chamber and the openings in the upper plate. 90

2. In a dyeing machine, in combination, a receptacle, a lower foraminous plate comprising a series of upwardly and downwardly converging elements with openings between said elements, an upper foraminous 95 plate comprising a series of upwardly and downwardly converging elements with openings between said elements spaced from the lower plate, means for maintaining the second plate at varying distances from the first plate, a fiber chamber formed by the two plates and the sides of the receptacle, means whereby air may be passed through the device, and means for forcing a liquid through the openings in the lower plate, the 100 fiber chamber and the openings in the upper plate. 105

3. In a dyeing machine, in combination, a receptacle, a foraminous fiber plate comprising a series of upwardly converging 110 elements with openings between said elements, a second foraminous plate within the receptacle, means for maintaining the second plate at varying distances from the first plate, a fiber chamber between the 115 plates, a liquid supply chamber below the first plate, a chamber below the supply chamber, a series of nested converging members within the last-mentioned chamber so arranged as to allow the passage between 120 them of a liquid from a pump chamber to the supply chamber, a pump chamber and means for forcing a liquid through the receptacle. 120

4. In a dyeing machine, in combination, a 125 receptacle, a foraminous fiber plate comprising a series of upwardly converging elements with openings between said elements, a second foraminous plate within the receptacle, means for maintaining the second 130

plate at varying distances from the first plate, a fiber chamber between the plates, a series of nested converging members below the first foraminous plate, means for forcing a liquid between the series of converging members, and means for returning the liquid from the top of the receptacle to the forcing means.

5. In a dyeing machine, in combination, 10 a receptacle, a lower foraminous plate comprising a series of upwardly and downwardly converging elements with openings between said elements, an upper foraminous plate comprising a series of upwardly and 15 downwardly converging elements with openings between said elements spaced from the lower plate, a fiber chamber formed by the two plates and the sides of the receptacle, means whereby air may be passed through 20 the device, a smaller testing device, similar and proportionate to, and exterior to the larger device, means connecting the spaces below the two lower foraminous plates for the passage of a liquid and means for forcing a liquid equally through the two devices.

6. In a dyeing machine, in combination, a receptacle, a lower foraminous plate comprising a series of upwardly and downwardly converging elements with openings 30 between said elements, an upper foraminous plate comprising a series of upwardly and downwardly converging elements with openings between said elements spaced from the lower plate, a fiber chamber formed by the 35 two plates and the sides of the receptacle, means for maintaining the upper plate at varying distances from the lower plate, a liquid supply chamber below the lower plate, a chamber below the supply chamber, a series of nested downwardly converging members 40 within the last-mentioned chamber so arranged as to allow the passage of a liquid between them, a pump, a smaller testing device, exterior of the larger device, having 45 foraminous plates, a fiber chamber and a supply chamber similar and proportionate to those of the larger device, means for connecting the two supply chambers for the 50 passage of a liquid and means for forcing a liquid through the two devices.

7. In a dyeing machine, in combination, a receptacle, a lower foraminous plate comprising a series of upwardly and downwardly converging elements with openings 55 between said elements, an upper foraminous plate comprising a series of upwardly and downwardly converging elements with open-

ings between said elements spaced from the lower plate, a fiber chamber formed by the two plates and the sides of the receptacle, 60 means for maintaining the upper plate at varying distances from the lower plate, a liquid supply chamber below the lower plate, a chamber below the supply chamber, a series of nested downwardly converging members 65 within the last-mentioned chamber so arranged as to allow the passage of a liquid between them, a pump, a smaller testing device exterior of the larger device, having foraminous plates, a fiber chamber and a supply chamber similar and proportionate to those of the larger device, means for connecting the two supply chambers for the 70 passage of a liquid, means whereby a liquid may be forced through the two devices, 75 means for returning the liquid for continuous circulation and means for conducting air equally through the two devices.

8. In a dyeing machine, in combination, 80 a receptacle, a foraminous fiber plate comprising a series of upwardly converging elements with openings between said elements, a second foraminous plate within the receptacle, means for maintaining the second plate at varying distances from the first 85 plate, a fiber chamber between the plates, a liquid supply chamber below the first plate, a chamber below the supply chamber, a series of nested downwardly converging members 90 within the last-mentioned chamber so arranged as to allow the passage between them of a liquid from a pump chamber to the supply chamber, a pump chamber, a top chamber above the fiber chamber, a series of nested upwardly converging members within the top chamber so arranged as to allow the passage of a liquid, means for forcing a liquid through the device, and means for conducting air through the device.

9. In a dyeing machine, in combination, a 100 receptacle, a foraminous fiber plate comprising a series of upwardly and downwardly converging elements with openings between said elements, a fiber chamber adjacent to the foraminous plate, means for forcing a liquid through the openings in the foraminous plate, and means for conducting air through the openings in the foraminous plate.

Signed at New York city, in the county 110 of New York and State of New York, this 29th day of January, 1917.

HOWARD M. DUDLEY.
